UNITED STATES PATENT OFFICE.

ISAAC C. POPPER, OF NEW YORK, N. Y.

PORTABLE COOKING APPARATUS.

1,260,798.

Specification of Letters Patent. Patented Mar. 26, 1918.

Application filed November 2, 1917. Serial No. 199,880.

To all whom it may concern:

Be it known that I, ISAAC C. POPPER, a citizen of the United States, residing at New York, in the county of New York and 5 State of New York, have invented certain new and useful Improvements in Portable Cooking Apparatus, of which the following is a specification.

My invention relates to an improvement 10 in a portable cooking apparatus and the object is to provide a light or simple device of few parts capable of all being nested together when not in use and of being fitted and placed in position so that several articles 15 can be cooked at the same time by the use of an ordinary alcohol or other burner.

Among the objects of my invention one is to provide means for protecting the flame against draft and another is to so 20 shape the receptacles that when assembled in one position they may be nested and when their position or order is reversed, they will be stacked one upon another in 25 convenient position to utilize all the heat units in the cooking operation.

A further object is to provide means for not only nesting and packing the various 30 parts together but also for fastening them in a close position so that all parts assembled and carried can be easily packed and stored and carried about from place to place.

In the accompanying drawings,

Figure 1 is a vertical section showing the 35 parts nested and in compact form;

Fig. 2 is a view of the pan which forms the cover;

Fig. 3 is a vertical section of the entire 40 apparatus when set up for use with the burner removed;

Fig. 4 is a view of the reversible rim; and Fig. 5 is a view of the base section.

The body portion of the cooker is preferably composed of the base section 1, and 45 the rim 2, base section 1, preferably has a closed bottom and the cylindrical side has openings for the ingress of air to support combustion and these are of such size and form as to preclude a draft of air of sufficient strength to blow out the flame, a burner of any suitable type 3, being placed in the center of this base section 1. The upper edge of the base section is rolled or crimped as at *a* to give added strength and 50 rigidity and a finished appearance and this is offset at 4, to form a support for the up-

per beaded or crimped edge 5, of the rim 2, when the latter is reversed and the cooker is in use, the lower rolled or crimped edge 6, of the rim being of smaller diameter and 60 extending inwardly so that the entire rim when right side up fits within the base section, as shown in Fig. 1, with its bead resting in the offset 4, at the upper edge of the base section.

The rim also has openings 7, in the cylindrical side for the escape of the products of combustion.

Provision is made by my invention for the use of three pans designated by the 70 numerals 8, 9 and 10, the two pans 8 and 9 being preferably approximately the same size and designated as deep pans to distinguish from the uppermost top or pan which is preferably of larger diameter but much 75 shallower than the other two. Obviously the invention might be modified in this regard as in others but it has been found that in this way ample provision is made for ordinary cooking with the idea of convenience 80 in nesting and packing away as well as in the actual practical use of the cooking apparatus.

The two deep pans 8 and 9 also differ somewhat in size, as one must be sufficiently 85 small to fit within the other. There is also another slight difference and that is in the larger pan 8, there is only one annular offset 11, at the top, whereas in the smaller deep pan 9, there are two annular offsets 90 12, and 13.

The upper and larger offset 12, affords a recess on the outer side for the bead of the larger pan 8, and the inner smaller offset 13, a shoulder upon which the larger pan 95 8, is supported during the cooking operation.

The edges of these several pans 8, 9 and 10 are rolled or crimped as at *b*.

The shallow pan 10, has a similar offset 100 14, in the bottom adapted to loosely fit the open upper end of the deeper pans 8 and 9 or the lower of the rim 2, when upturned to prevent its sliding off. When the various pans are all nested together the rim 2 105 and both of the deep pans 8 and 9 fit within the base section 1, and the shallow pan 10, is turned over and just fits the outer rim of the base section as shown in Fig. 1, and the several crimped or beaded edges *a* and *b* engage one another, and two at least of them 110 are engaged by the pan, as shown in Fig. 1,

when the parts are nested so that when the strap 14 is pulled tight and fastened and everything is packed together, the binding effect is such that it absolutely precludes the 5 possibility of the various pans moving or rattling.

The loops 15, at the sides are adapted to receive a strap 16, or other fastening means for holding the various parts together.

10 It is understood that where a burner such as 3, or its equivalent is used, there is ample room in the center of the inside pan to receive it.

15 In addition to this there is space for various utensils such as knife, fork, spoon and holder as well as a bottle to receive alcohol or other fuel.

20 The entire device is thus made of few parts, that is to say, five in all, in addition to the burner which are of simple form and easy to construct, capable of being perfectly nested and packed in small compass when not in use and when in use quickly and easily set up and adjusted so that from one 25 to three different articles of food can be cooked at one and the same time.

I claim:

1. As an article of manufacture, a portable cooking apparatus comprising nestable 30 members, the edges of which are beaded or crimped and constructed and adapted to fit one another, and when nested are contiguous, one of the members shallow and adapted to act as a cover when the members are 35 nested, its form and dimensions being such

that it embraces and engages at least two of the beaded or crimped edges of the nested members, and external means for clamping the shallow member tightly in position, whereby to cause it to have a binding effect 40 to hold the several nested members rigidly together when nested, thereby precluding any possibility of shaking or rattling of said members.

2. As an article of manufacture, a portable cooking apparatus comprising nestable members, the edges of which are beaded or crimped and constructed and adapted to fit one another, and when nested are contiguous, one of the members shallow and adapted to act as a cover when the members are 50 nested, its form and dimensions being such that it embraces and engages at least two of the beaded or crimped edges of the nested members, and external means for clamping 55 the shallow member tightly in position, whereby to cause it to have a binding effect to hold the several nested members rigidly together when nested, thereby precluding any possibility of shaking or rattling of 60 said members, said clamping means consisting of a strap slidably and removably connected with one of the members, which, when fastened tight, maintains this rigid binding relation between the several nested 65 members.

In testimony whereof I, affix my signature.

ISAAC C. POPPER.
